CLAIM

The ornamental design for a wire tang casting, as shown and described.

DESCRIPTION

FIG. 1 is a perspective view of the wire tang casting of the instant invention.

FIG. 2 is a front view of the casting shown in FIG. 1.

FIG. 3 is a rear view of the casting shown in FIG. 1.

FIG. 4 is a side view of the casting shown in FIG. 1. The opposite side view is the mirror image.

FIG. 5 is a top end view of the casting shown in FIG. 1; and, FIG. 6 is a bottom end view of the casting shown in FIG. 1.
